UNITED STATES PATENT OFFICE.

PATRICK BROWN, OF BUFFALO, NEW YORK.

CAR-COUPING.

SPECIFICATION forming part of Letters Patent No. 715,970, dated December 16, 1902.

Application filed May 5, 1902. Serial No. 105,937. (No model.)

To all whom it may concern:

Be it known that I, PATRICK BROWN, a citizen of the United States, residing at Buffalo, in the county of Erie and State of New York, have invented new and useful Improvements 5 in Car-Couplings, of which the following is a specification.

This invention relates more particularly to an improvement in twin-jaw car-couplings of 10 the Janney type. In couplers of this class when an empty or lightly-loaded car is coupled to a heavily-loaded car the coupling of the light car stands more or less above that of the heavy car. The knuckles, therefore, do 15 not interlock throughout their full depth or coupling-surface, but only the lower portion of the high coupling interlocks with the upper portion of the low coupling, thus bringing the draft strain upon a comparatively 20 small area of the coupled knuckles and exerting the same in an indirect manner, liable to cause breakage of the knuckles in case either should contain a flaw or other weakness. Moreover, in such couplings as ordinary 25 narily constructed the knuckles are free to separate under a vertical movement of greater extent than that of the contact-surfaces of the knuckles, and in case a draw-bar should be broken or pulled out of place it is wholly 30 unsupported and liable to drop upon the track. It is well known that trains have frequently been derailed and wrecked by such fallen draw-bars.

One of the objects of my invention is to provide 35 an improved coupler of simple construction in which the coupling-surfaces of the knuckles are fully utilized under all ordinary conditions regardless of the relative elevations of the coupled draw-heads.

A further object of the invention is to so construct the couplings that they cannot become separated by an excessive or abnormal vertical movement, but remain coupled even if one of the draw-bars should become wholly 45 disconnected from the car, thus preventing a broken or detached draw-bar from falling upon the track and causing an accident.

In the accompanying drawings, consisting 50 of two sheets, Figure 1 is a side elevation of a pair of connected car-couplings embodying my invention. Fig. 2 is a vertical longitudinal section of the same. Fig. 3 is a horizon-

tal section in line 3 3, Fig. 2. Fig. 4 is a transverse vertical section in line 4 5, Fig. 1, looking in the direction of the arrow. Fig. 55 5 is a section in the same line looking in the opposite direction. Fig. 6 is a top plan view of the coupling, showing the knuckles open preparatory to being closed by the coupling bar or link. Fig. 7 is a perspective view of 60 the coupling-link. Fig. 8 is a horizontal section of a modified construction of the link designed for connecting my improved coupler to an ordinary Janney coupler. Fig. 9 is a transverse vertical section in line 9 9, Fig. 8. 65 Fig. 10 is a perspective view of said modified link.

Like letters of reference refer to like parts in the several figures.

A indicates the hollow or chambered draw-head, which has the general contour of a Janney coupler, except that the portion thereof corresponding to the customary horn or guard of the Janney coupler is symmetrical in construction with the opposite side of the draw-head. 70

Instead of having a single knuckle like the Janney coupler the draw-head is provided in its front portion with a pair of knuckles B B, arranged to face each other and pivoted to 80 swing horizontally on upright pins b. These pins pass through the hubs of the knuckles and are seated in openings in the top and bottom of the draw-head. Each of the twin knuckles B has an inwardly-extending jaw b' 85 and a rearwardly-extending tailpiece b², substantially like the corresponding members of a Janney knuckle. The outer faces of the knuckles are straight and in line with each other in the closed position of the knuckles, 90 as best shown in Fig. 3, and their opposing jaws are separated by an intervening space.

Any suitable or approved automatic lock may be employed for locking the knuckles. The preferred lock (shown in the drawings) 95 consists of a vertically-swinging gravity-block C, pivoted in the central portion of the draw-head by a transverse pin c and arranged to hang between the opposing tailpieces b² of the twin knuckles when in its normal position for simultaneously locking both knuckles, as shown in Fig. 3. The knuckles are unlocked by swinging the lock rearwardly 100 clear of their tailpieces. In the construction

shown in the drawings the lock is raised out of engagement with the tailpieces by a sliding pull-bar D, guided in openings d d' , formed in the top and bottom of the draw-head and pivoted by a transverse pin e to a bifurcated arm or lug e', extending rearwardly from the free lower end of the lock and rigidly secured thereto or formed thereon. The unlocking-bar D has a perforated head d^2 , to which the usual pull rod or chain (not shown in the drawings) is attached.

As shown in Fig. 3, the tailpieces of the knuckles are provided with rounded rear sides, which deflect the gravity-lock rearwardly when the knuckles are closed, automatically locking the latter in a well-known manner. Two of such draw-heads are coupled together by an independent coupling bar or link F, which is constructed to positively connect the opposing pairs of knuckles in such manner that they cannot under any circumstances become separated by a vertical movement of the couplings upon each other. I prefer to employ for this purpose the link shown in the drawings and consisting of a strong bar arranged vertically between the draw-heads and provided in opposite sides with comparatively long longitudinal grooves, guides, or recesses f, adapted to receive the opposing jaws of the knuckles carried by one of the draw-heads and having lateral extensions or auxiliary recesses f', which are adapted to receive the opposing jaws of the knuckles carried by the other draw-head. The flanges or shoulders f² f³, formed by the front and rear walls of the recessed link, engage behind the two sets of knuckle-jaws, as shown in Fig. 3, while the web f⁴, which separates the two sets of recesses f f', occupies the space between the opposing jaws of the two pairs of knuckles, as shown in the same figure and in Figs. 4 and 5. The short grooves or recesses f' are formed in a lateral extension f⁵ of the coupling-link and are just long enough to easily admit the adjacent pair of jaws, so as to hold the link against vertical displacement on the same. The long grooves f of the link are considerably longer than the depth of the knuckle-jaws engaging there-with to compensate for differences in the elevation of the coupled draw-heads and to permit the jaws to play freely up and down on the link, and vice versa, in following the vibrations of the cars. The end walls or flanges f⁶ of the link form stops which prevent the link from becoming disengaged from the knuckles, which play in its long grooves f.

It will thus be observed that while the two sets of knuckles are reliably coupled together and free to play vertically, as in the ordinary Janney coupler, they cannot become disconnected by an abnormal vertical movement, but are inseparably linked together by the coupling-bar F so long as the knuckles remain locked. In case a draw-bar should in any way become detached from the draft-rigging of the car it will therefore remain at-

tached to the draw-bar of the adjoining car and be supported and carried clear of the track by the same, averting an accident to 70 the train, which might otherwise occur.

Under normal running conditions the coupling-link F affords the advantage of providing a full and wide bearing of the knuckle-jaws, irrespective of whether one of the coupled draw-heads is more or less out of horizontal alignment with the other, thus exerting a practically even draft upon the couplings and reducing the liability of breakage to a minimum.

In coupling two cars equipped with my improved coupler the coupling-link F is interlocked with the knuckles of one of the opposing draw-heads by opening the knuckles and then forcing the enlargement f⁵ of the link against their tailpieces, which causes the jaws of the knuckles to swing toward each other and enter the short recesses f' of the link, the jaws fully entering the latter by the time the knuckles reach their locked 90 position, as shown in Fig. 3. The knuckles of the opposing draw-head are now opened and as the cars come together the free or front side of the coupling-link strikes the tailpieces of the knuckles, closing and locking the latter and causing their jaws to enter the long grooves f of the link. The automatic locking action of the coupling is thus similar to that of ordinary knuckle-couplings. The link is made of the proper length to meet 100 extreme variations in the height of empty and loaded cars, and the lateral extension f⁵ of the link which contains the short recesses f' is arranged midway of the length of the link, so that the latter extends above and below the draw-head, whose knuckles are interlocked with the short recesses. By this arrangement the link upon being interlocked with the first draw-head extends above the latter far enough to encounter with certainty 110 the tailpieces of the knuckles on the opposing draw-head. In case both of two cars to be coupled have links interlocked with their knuckles one of the links is removed before 115 making the coupling.

From the foregoing description it will be seen that by my improved construction an automatic coupling is obtained which retains the advantages of the approved type of couplers in general use, and yet overcomes a recognized objection to such couplers—viz., their complete separation in case of breakage or pulling out of a draw-bar.

In order to permit the knuckles of my improved coupling to be coupled to another car 125 by an ordinary link-and-pin coupling, the jaws of the knuckles are bifurcated or recessed, as shown at g, and provided with pin-holes g'. The coupling-link F is preferably provided in its short recesses f' with central lugs f⁷, 130 which are adapted to interlock with the recesses g of the knuckle-jaws. To enable a car equipped with this improved coupling to be coupled to one having an ordinary Janney

coupler, the coupling-link is modified in construction, as shown in Figs. 8 to 10. In this case the body of the link consists of a transverse vertical web F', provided on one side 5 midway of its width with a projecting lug or head f⁸, having locking-recesses f⁹ in opposite sides for the reception of the knuckle-jaws of my coupler. On its opposite side the web F' is provided with a second head f¹⁰, 10 having in one side a vertical locking groove or recess f¹¹, constructed to receive the knuckle-jaw of the opposing Janney coupler. The head f¹⁰ is attached to the knuckle of the Janney coupler by a pin f¹², passing through 15 the jaw of the knuckle and through openings in the top and bottom of the recess f¹¹ and in an intermediate rib f¹³.

I claim as my invention—

1. A draw-head having twin coupling jaws 20 or knuckles pivoted to swing horizontally in the head and each provided with a tailpiece, the tailpieces of the two knuckles being separated in the closed position of the knuckles, and a lock constructed to enter between the 25 opposing tailpieces of the knuckles, substantially as set forth.

2. A draw-head having twin coupling jaws or knuckles pivoted to swing horizontally in the head and each provided with a tailpiece, 30 and a vertically-swinging lock arranged to enter between the opposing tailpieces of the knuckles, substantially as set forth.

3. The combination of a draw-head having a horizontally - swinging knuckle provided 35 with a tailpiece, a depending lock pivoted to swing lengthwise in the draw-head and provided at its lower end with a rigid rearwardly-extending arm, and an unlocking device connected with said arm and extending through 40 the draw-head, substantially as set forth.

4. The combination of a draw-head having a horizontally - swinging knuckle provided with a tailpiece, a depending lock pivoted to swing lengthwise in the draw-head and provided at its lower end with a rigid rearwardly-extending arm, and a vertically movable unlocking-bar guided in the draw-head and pivoted to the arm of the lock, substantially as 45 set forth.

5. The combination of two draw-heads each having a pair of opposing coupling - jaws, means for locking said jaws in their coupling position, and a coupling-link adapted to stand vertically between the draw-heads, said link 55 being constructed to interlock with the opposing pairs of jaws and provided with stops for limiting the vertical movement of the link and the jaws relatively to each other, substantially as set forth.

6. The combination of a pair of draw-heads each having a coupling-jaw, and a coupling-link adapted to stand vertically between the draw-heads and provided midway of its ends with attaching means constructed to engage 65 with the coupling-jaw of one of the draw-heads and with a vertical guide adapted to

receive the coupling-jaw of the other draw-head and arranged to extend above and below said attaching means, substantially as set forth.

7. A link for car-couplings, consisting of a bar adapted to stand vertically between a pair of opposing draw-heads and provided midway of its length with attaching means constructed to engage with the coupling-jaw of one of the draw-heads and with a vertical guide adapted to receive the coupling-jaw of the opposing draw-head and arranged to extend above and below said attaching means, substantially as set forth. 70

8. The combination of two draw-heads each having a pair of opposing coupling jaws or knuckles pivoted to swing horizontally in the head and provided with tailpieces, locks for said knuckles, and a coupling-link adapted 85 to stand vertically between the draw-heads and provided in opposite sides with locking-recesses arranged to receive the opposing knuckles of the two draw-heads, substantially as set forth. 80

9. The combination of two draw-heads each having a pair of opposing coupling jaws or knuckles pivoted to swing horizontally in the head and provided with tailpieces, locks for said knuckles, and a coupling-link adapted 95 to stand vertically between the draw-heads and provided in opposite sides with longitudinal locking grooves or recesses closed at their ends and adapted to interlock with the knuckles of the two draw-heads, substantially 100 as set forth. 90

10. The combination of two draw-heads each having a pair of opposing coupling jaws or knuckles pivoted to swing horizontally in the head and provided with tailpieces, locks for 105 said knuckles, and a coupling-link adapted to stand vertically between the draw-heads and provided in opposite sides with longitudinal locking grooves or recesses which are of greater extent than the jaws of the knuckles 110 and adapted to receive the jaws of one of the draw-heads, and which are provided midway of their length with lateral extensions constructed to receive the jaws of the other draw-head, substantially as set forth. 115

11. A link for car-couplings, having longitudinal flanges or shoulders constructed to interlock with the coupling-jaws of two opposing draw-heads and stop flanges or shoulders arranged at the ends of the longitudinal 120 flanges, substantially as set forth.

12. A link for car-couplings, consisting of a bar provided in opposite sides with longitudinal grooves having lateral extensions arranged about midway of their length, substantially as set forth. 125

Witness my hand this 1st day of May, 1902.
